UNITED STATES PATENT OFFICE.

DANA E. HARDING, OF ARLINGTON, MASSACHUSETTS, ASSIGNOR TO HARDING ENGINEERING COMPANY, OF EAST BOSTON, MASSACHUSETTS, A CORPORATION OF MASSACHUSETTS.

STAKING MACHINE.

Application filed August 18, 1925. Serial No. 51,006.

My present invention relates to leather working machines, and more particularly to an improved staking machine.

In the manufacture of leather from hides and skins, an important step in the process is the softening of the leather before having certain operations performed thereon such, for example, as glazing or boarding. The leather, as it comes from the drier, is hard and stiff and before certain necessary operations are performed thereon, the leather must be made pliable while still in the nearly dry condition. At present this operation known as staking is performed on the staking machine in which a pair of cooperating and rapidly reciprocating staking elements grasp the leather at any desired point and are rapidly pulled away from the leather, such elements coming to the edge of the leather releasing themselves therefrom. During this operation the leather must be held against the force exerted by the members by the operator of the staking machine. This staking operation is what is usually known in tanneries as the man killing job because of the fact that numerous accidents, some of which are fatal, occur because of the rapidly reciprocating members above referred to, and also accidents in the nature of strain or rupture frequently occur because of the fact that it has heretofore been necessary for the operator to hold the leather against the tension exerted by the machine.

With a view to overcoming objections in prior structures and to produce a machine in which all of the work except guiding is performed by the machine, I have devised the present apparatus and in such apparatus have substituted for the reciprocating staking members a pair of cooperating endless chains such chains being provided at intervals with staking members operating in association with each other, and also associate with said members a work clamping means automatically operated in synchronism with the staking elements.

The principal object of my invention, therefore, is an improved staking machine.

Another object of my invention is an improved clamping means for staking machines and the like.

Other objects and novel features of the construction and arrangement of parts comprising the structure will appear as the description of the invention progresses.

In the accompanying drawings illustrating the preferred embodiment of my invention,

Fig. 1 is a side elevation;

Fig. 2 is a front elevation, partly in section;

Fig. 3 is a plan view, partly in section;

Fig. 4 is a perspective view of the work supporting table, and

Fig. 5 is a perspective view of the base or pedestal of the machine.

Referring to the drawings, 10 designates a base, at one end of which are formed upwardly and rearwardly extending members 11 and 12 respectively. Secured to the portion 12, spaced apart from each other and on each side of such portion 12, are downwardly extending plates or straps 13. Secured to the straps 13 on each side of the portion 12 substantially horizontal and spaced apart from each other are straps 14, the rear end of these straps being secured by bolts 15 to the upright portion 11. The straps 13 and 14 constitute a rectangular framework. Secured to the inner faces of the members 14 and in alignment with each other are substantially rectangular frames 16, the ends of which are rounded, as indicated at 17, and such members form tracks for elements to be hereinafter described. Secured to the inner faces of the ends of each of the rectangular frames 16 in advance, or to the left of the upright member 13, are bearings 18, such bearings being in alignment with each other, and in these bearings is rotatably mounted a shaft 19. Secured to the shaft 19 between the bearings 18 is a sprocket 20 of suitable pitch and diameter. Secured to the inner face of each of the rectangular frames 16 adjacent to, and in advance of, the left hand members 13, as viewed in Fig. 1, are bearings 24 and in the bearings 24 is rotatably mounted a shaft 25, this shaft being parallel to the shaft 19. Secured to the shaft 25 between the bearings 24 is a sprocket 26 similar in pitch and diameter to the sprocket 20 on the shaft 19. Over the sprockets 20 and 26 runs an endless chain 27. Secured to the endless chain 27 at intervals is a device comprising spaced links 28 in which and at each end of which are secured parallelly arranged shafts 29. Rotatably mounted on the shafts 29 and at the end thereof are rollers 30, the washer 31 and cotter pin 32 maintaining such roll-

ers in operative position on the shafts 29. The rollers 30 engage with the outer periphery of the rectangular frames 16 and the rounded ends 17 of which frames engage 5 with the rollers 30 to guide the members 28 and attached parts therearound. Secured to, and extending outwardly on, the members 28 with respect to the conveyor 27 is a block 33 to each side of which and trans- 10 versely of the conveying chain 27 is secured an outwardly extending plate 34 by means of bolts 35. The plates 34 are, as will be seen from an inspection of Fig. 1, spaced apart from each other and their outer ends 15 are rounded and they form, with the blocks 33, a substantially rectangular trough. Secured to the lowermost portion of the plates 13 on each side of the rectangular framework by bolts 36 are bars 37, such bars lying 20 parallel to the members 14 and spaced apart from the lowermost plate 14 a distance substantially equal to the diameter of the rolls 30, these bars acting, with the lower surface or edge of the rectangular frame 16, to prevent 25 a tilting of the members 28 with respect to the line of movement thereof.

Secured to the base 10 and extending upwardly therefrom on each side thereof, in a manner similar to the straps 13 on the portion 30, 12, are straps 38, and secured to the straps 38 lying substantially horizontal and spaced apart from each other are straps 39, these straps being similar to the straps 14 above described. The rearmost portion of 35 the straps 39 are attached to the upright portion 11 by bolts 40. Secured to the inner faces of the straps 39 are substantially rectangular frames 41, the ends of which are rounded, as indicated at 42. On the 40 inner faces of the rear ends of the rectangular frames 41 in front of the upright 11 are bearings 43, but one of which is shown, similar to the bearings 18 above described, and in such bearings is rotatably mounted a 45 main drive shaft 44, this shaft lying beneath and parallel to the shaft above described. This shaft 44 extends laterally outward beyond the limits of the rectangular structure above described and on such shaft are mounted the tight and loose pulleys 45 and 46 respectively, a collar 47 secured to the end of the shaft 44 preventing longitudinal movement of the loose pulley 46 thereon. Over the pulleys 45 and 46 50 may run a belt 48 leading from any suitable source of power. On the end of the shaft 44 remote from the pulley 45 is keyed a bevel gear 49 which meshes with, and drives, a similar bevel gear 50 keyed to the lower end of a shaft 51 that is mounted for rotation in the vertical bearings 52 and 53 secured to the uppermost longitudinal member 39 and the lowermost longitudinal member 14 respectively. Secured to the upper 55 end of the shaft 51 is a bevel pinion

which meshes with and drives a bevel pinion 55 keyed to one end of the shaft 19. It is obvious that, if power is transmitted to the shaft 44 through the belt 48 and tight pulley 45, rotation of the shaft 44 will, through 70 the train of gears just described, cause a rotation of the shaft 19 at the same speed and in the same direction, it being assumed that the train of gears provides for equal angular speed of the shafts 44 and 19. Between the bearings 43 and on the shaft 44 is secured a sprocket 56. Secured to the inner faces of the front ends of the rectangular frames 41 are bearings 57. In the bearings 57 is rotatably mounted a shaft 58 and 75 secured to such shaft between the bearings 57 is a sprocket 59, this sprocket being in alignment with the sprocket 56 above described as being secured to the shaft 44. The sprockets 56 and 59 are equal to each other in pitch and diameter and are also equal in pitch and diameter to the pitch and diameter of the sprockets 20 and 26, and over the sprockets 56 and 59 runs an endless chain 60. Secured at intervals along 80 the length of the chain 60 is a staking member comprising a substantially U-shaped member 61 having at one side thereof members 62 through which pass pins 63 for attaching the same to the chain 60. At each 85 end of the element 61 lying parallel to each other and transversely to the direction of travel of the chain 60 are shafts 64. On the outer ends of these shafts 64 are rotatably 90 mounted bearing rollers 65, these rollers being adapted to roll on the outer periphery of the rectangular frames 41. Secured to the inner faces of the uprights 38 by bolts 66 and lying parallel to the under edge of 95 the lower reach of the rectangular frames 41 are bars 67, these bars being spaced apart from the rectangular frames 41 a distance substantially equal to the diameter of the rolls 64 and these bars 67 act in conjunction 100 with the rectangular frame 41 as means for preventing a rocking movement of the member 61 and parts carried thereby about the pivotal connection 63 thereof on the chain 60. Secured to projecting portions 68 on 105 the member 61 is a shaft 69 and on said shaft is rotatably mounted the roller 70, the diameter of this roller 70 being less by slightly more than twice the thickness of the ordinary sheet of leather 71 than the 110 distance between the parallelly arranged elements 34 carried on the members 28. This construction allows the leather 71 to assume the position indicated in Fig. 1 when the parallelly arranged members 34 cooperate 115 with the roller 70 and, if means is provided for holding the leather 71 stationary, it is obvious that the swell or wave formed in such leather will move to the right, as shown in Fig. 1, until the elements 34 and 70 become 120 disengaged from the leather. The 125 130

shafts 44 and 19, rotating at the same surface speed and in the same direction, it is obvious that the elements 34 and 70 that are now shown in association with each other will maintain their relative position throughout the entire travel of the lower reach of the chain 27 and the upper reach of the chain 60. Associated with the structure above described is a work table shown in Fig. 4, this table comprising essentially a plurality of supporting legs 72 of any convenient size and height, and on such legs is secured a table top 73 provided at one side with a downwardly depending apron 74. Corner braces 75 are provided for strengthening the structure. The table top 73 is cut away, as indicated at 76, to allow the same to be pushed into position with the cut away portion 76 in alignment with the line of travel of the members 61 and parts carried thereby, the upper surface of the table top 73 lying in the same horizontal plane in which the center of the shaft 69 runs when moving to the right, as viewed in Fig. 1.

The shaft 25 extends laterally outward at one side of the rectangular framework above described and on this extension is secured a pinion 77. This pinion 77 meshes with, and drives, a gear 78 rotatably mounted on a stub shaft 79 that is secured to a bracket 80 secured to the outer forward end of one of the rectangular frames 16. Secured to the outer face of the gear 78 is a block 81. Pivotally secured to the outer ends of the bars 37 is a U-shaped member 82, this member being provided with a downwardly extending face 83 adapted to engage with the leather 71 on the front end of the table top 73 and with a rearwardly extending arm 84. This arm 84 has secured thereto a block 85 adapted to be engaged by the block 81 on the gear 78 in the rotation of the gear. Secured to the free end of the arm 84 is the lower end of a coil spring 86, the upper end of this coil spring being attached to the outer end of a pin 87 screwed into the rectangular framework 41. The spring 86 normally rotates the U-shaped member 82 about its pivot points so as to bring and hold the flat surface 83 in engagement with the sheet of leather 71 on the table top 73, but periodically in the rotation of the shaft 25 the block 81 on the gear 78 is brought into engagement with the block 85 on the arm 84 and thus rotates the U-shaped member about its pivot points against the tension of the spring 86 and leaving the flat surface 83 out of engagement with, and therefore freeing, the leather 71 on the table top 73. By referring to Fig. 1, it will be noted that there are two of the blocks 28 with attached elements 34 and also two of the members 61 with attached rollers 70. Further, it will be noted that these elements on the same chains

are arranged practically equi-distant from each other. The pinion 77 and gear 78 are so proportioned with the length of the chains 27 and 60 and the position of the elements 28 and 61 thereon that when, for example, 70 the elements 34 and 70 that are now shown in engagement with the sheet of leather 71 and in association with each other move off the table top 73 and before the next set of elements 34 and roller 70 have come into 75 association, the blocks 81 and 85 will become engaged to lift the flat portion 83 of the U-shaped member 82 off the leather 71 to release the same and will allow such blocks to move out of engagement again to bring 80 the member 83 into the position shown in Fig. 1 just before the next succeeding elements 34 and 70 come into action. During this period of release, the operator will have time to shift the sheet of leather on the 85 table top 73 to any position desired to thus bring a new portion of the leather 71 into position to be operated on by the elements 34 and 70.

The operation of my improved apparatus 90 is as follows, it being assumed that it is desired to render pliable a dried sheet of leather 71 prior to performing a certain necessary or desirable operation thereon. The operator throws power into the machine by 95 moving the belt 48, leading from a source of power, from the loose pulley 46 onto the tight pulley 45, this causing a rotation of the drive shaft 44 and therefore the simultaneous operation of the chains 14 and 39 100 at equal speeds and in the direction of the arrows indicated in Fig. 1, and also causes intermittent operation of the clamping device 82, 83 as above described. During one of the times when the flat clamping member 105 83 is moved up from the table 73, the operator slides a hide 71 into the position indicated in Fig. 1 and shortly after the clamping member 83 moves into the position shown in Fig. 1 and clamps a hide 71 110 on the table 73. The members 28 and 61 on the chains 14 and 39 respectively move with said chains and come into association with each other, the elements 34 on the member 28 being above the hide 71 and the element 70 on the member 61 being below the hide 71. The clamping member 83 holds the hide 71 against movement and the elements 34 and 70 are drawn across the hide 71, flexing the same in a path as wide as the elements 34 and 70, this action rendering the leather worked upon very flexible. When the elements 34 and 70 disengage from the hide 71, the block 81 on the gear 80 will move into engagement with the block 85 on 120 the arm 84 which will cause a rotative movement of the U-shaped member 82 about its pivot points, lifting the clamping member 83 off the hide 71. The hide 71 is now free 125 to be moved and the operator thereupon 130

moves the same into a new position on the table top 73 so as to bring an unworked portion of the hide 71 into position to be engaged by the next succeeding members 34 and 70. Just before the next succeeding members 34 and 70 come into engagement with the hide 71, the block 81 will have moved out of engagement with the block 85 and the spring 86 will rotate the U-shaped member 82 about its pivot points and bring the member 83 into clamping position. This sequence of operations is repeated until the entire hide 71 has been worked over and rendered flexible and the sequence of operations may be continued indefinitely on succeeding hides.

While I have necessarily shown and described the preferred embodiment of my invention somewhat in detail, it is to be understood that I may vary the size, shape and arrangement of parts within wide limits without departing from the spirit of the invention.

Having thus described my invention, what I claim as new is:

An improved staking machine comprising

a pair of endless chains parallelly arranged with respect to each other and having adjacent reaches spaced apart from each other and defining a passage for the reception of work, a work support associated with said chains, and having its upper surface lying in a plane between the adjacent reaches of the chains, means associated with said chains for maintaining adjacent reaches parallel to each other at all points and under all conditions, means for moving adjacent faces of said chains in the same direction and at the same speed, staking elements carried by said chains and cooperating with each other to perform a flexing operation on work held in the work support, clamping means for holding said work on said support against movement during the operation of the staking means, and means associated with said chains for releasing said clamping means only after the staking means has performed its function.

In testimony whereof, I have signed my name to this specification.

DANA E. HARDING.
